G. Henry Hulskamp

United States Patent Office.

G. HENRY HULSKAMP, OF NEW YORK, N. Y.

Letters Patent No. 66,347, dated July 2, 1867.

IMPROVEMENT IN VIOLINS, &c.

The Schedule referred to in these Letters Patent and making part of the same.

TO ALL WHOM IT MAY CONCERN:

Be it known that I, G. HENRY HULSKAMP, of the city of New York, have invented new Improvements in Violins, Guitars, etc.; and I do hereby declare that the following is a full and exact description thereof, reference being had to the annexed drawings which are in small size. The same letters refer to like parts in each.

Figure 1 is a horizontal plan of a violin.

Figure 2 is a vertical plan as seen from the right-hand side of the instrument.

Figure 3 is also a vertical section as seen from the right-hand side.

Figure 4 is a transverse vertical section of the finger-board.

I have heretofore applied the principle of straining the sounding-boards by screws, to violins, guitars, alto violins, violincellos, bass violins, etc., by which the tone and power of these instruments have been much improved. I have now applied the same principle to these instruments by a different construction and in a less expensive manner. The drawings represent the improvements applied to a violin. The application to the other instruments is substantially in the same way.

a a a represent a united finger-board and string-holder, made out of one or more different pieces of wood or other material, and secured to the neck *b* and to the end of the instrument at *c*. In the finger-board is an orifice, *O*, fig. 1, through which the bridge *k* passes without touching the finger-board. The form of the finger-board at *O* is represented in transverse vertical section, through the middle at fig. 4, and *k* represents the bridge. An oblique brace, *d d*, is firmly secured with both its ends to the pieces of wood *e e*, and to the ends of the upper sounding-board, in the inside of the middle of the instrument. *f* is a screw in the string-holder, which extends through an orifice in the upper board into the oblique brace *d d*. By tightening this screw *f* and the strings of the instrument, the upper sounding-board will be strained. The oblique brace *g g* in fig. 2 is firmly secured to the inside of the lower sounding-board. The upper end of the oblique brace, fig. 2, at *h*, extends up through the orifice *i* in the upper board, without touching the same, to the upper surface of the upper sounding-board. One foot of the bridge *k* is placed upon this post and the other foot upon the surface of the upper sounding-board. The vibration of the springs is transmitted alike to both the points *g g* of the lower sounding-board, and by the pressure of the strings upon this oblique post the sounding-boards will also be strained. The oblique post or brace *g g*, in fig. 3, is also secured to the lower board in the same manner as the brace in fig. 2. But its upper part *m* is placed under the upper sounding-board, near to the other foot of the bridge *k*. It will be seen that the straining of the board in this figure is in the same manner produced as in fig. 2. Straining the sounding-boards in this manner, and transmitting the vibrations of the strings through oblique braces to different points of the sounding-boards, the tone and power of the instrument are much improved, and this system of straining the sounding-boards, with similar oblique braces and a solid finger-board, can also be easily applied to all instruments of the old construction. I can dispense with the string-holder entirely by extending the finger-board to the line *p* and securing the string *n* directly on the end of the finger-board at *p p p*, but in large instruments I prefer the united finger-board and string-holder, screwed firmly to the end of the instrument at *c*. By placing the feet of the bridge on different posts, or on the upper and lower board of the instrument, the tone of the instrument can be varied.

What I claim as my invention, and desire to secure by Letters Patent, is—

1. I claim the straining of sounding-boards in violins and other instruments before named and referred to, of whatever material made, by the tension and pressure of the strings, substantially as hereinbefore described.
2. Transmitting the vibration of the strings by posts or oblique braces to different points of the upper and lower sounding-boards, and making the feet of the bridge *k* to bear upon the oblique braces, substantially as described.
3. Making the finger-board and string-holder in one piece, with an orifice *O* for the bridge *k*, and connecting the same with the oblique brace *d d*, substantially as set forth.
4. Securing the strings directly on the end of the extended finger-board at *p p p*, substantially as described.

G. HENRY HULSKAMP.
